UNITED STATES PATENT OFFICE.

JOSEPH M. SCHUTZ, OF MINNEAPOLIS, MINNESOTA, ASSIGNOR TO THE SCHUTZ-O'NEILL COMPANY, OF SAME PLACE.

SEPARATOR.

SPECIFICATION forming part of Letters Patent No. 619,353, dated February 14, 1899.

Application filed May 4, 1897. Serial No. 634,991. (No model.)

To all whom it may concern:

Be it known that I, JOSEPH M. SCHUTZ, of the city of Minneapolis, county of Hennepin, State of Minnesota, have invented certain new and useful Improvements in Separators, of which the following is a specification.

My invention relates to milling-machines; and the object of the invention is to provide a high-speed mill or pulverizer with means whereby the coarse material may be held in the machine while the fine material is driven or conducted therefrom.

The further and particular object of the invention is to provide means by which the separation may be regulated so that all grades from the coarsest material that could pass through the mill to the finest impalpable powder may be obtained.

A further and particular object is to provide means for taking care of the coarse material which is prevented from escaping at the outlet and for again discharging such coarse material into the mill.

My invention consists in the combination, with the pulverizer proper, of means for creating a strong current of fluid, such as air or water, through the same, an outlet from the pulverizer, and an incline therefrom whereon the heavier particles are stopped and returned to the pulverizer, while the lighter particles are carried off by said current.

My invention further consists in means for accelerating the action of the air-currents at the point of separation.

My invention further consists in means for regulating the action of the air-currents whereby various grades of material may be taken from the pulverizer.

My invention further consists in the combination, with the mill-pulverizer proper and the outlet thereof, of means whereby the material is worked toward the front or forward end of the pulverizer and an elevator or conveyor opening into the body of the pulverizer at a point near the outlet thereof to take the coarse material and return the same to the inlet of the pulverizer.

The invention further consists in constructions and combinations of parts, all as hereinabove described, and particularly pointed out in the claims.

The invention will be more readily understood by reference to the accompanying drawings, forming part of this specification, and in which—

Figure 1 is a side elevation of a pulverizer and separator embodying my invention. Fig. 2 is a front elevation of the same enlarged. Fig. 3 is a longitudinal and vertical section of the pulverizing-machine on the line *x x* of Fig. 2. Fig. 4 is a partial transverse vertical section on the line *z z* of Fig. 3. Fig. 5 is an enlarged detail section showing the means for moving the adjusting-rod which is within the main drive-shaft. Fig. 6 is an enlarged detail taken from Fig. 3. Fig. 7 is a horizontal section on the line *u u* of Fig. 2. Fig. 8 is a vertical section on the line *y y* of Fig. 7. Fig. 9 is a vertical and longitudinal section showing a modified form of pulverizer, the same being provided with a separator or grader embodying my invention.

In the drawings I have shown a complete machine, though I shall not claim in this application several new inventions shown therein, and such parts will not be particularly described. The base 2 is provided with bearings 3 and 4 for a main driving-shaft 5, which driving-shaft is provided with a longitudinal hole 6 to receive the adjusting-rod 7, which rod is moved longitudinally by means of the hand-screw 8. Any suitable antifriction means 9 may be interposed between the end of the screw 8 and the thrust or adjusting rod 7. Upon the forward end of the base 2 is the annular body 10 of the machine. The inner end 11 of the body has a central hole 12 around the shaft 5, through which hole the material is fed from the trunk 13. The inside of the body 10 is lined with a removable corrugated shell 14, the opening within which is smaller at the outer end than at the inner end, whereby the action of the rotating parts or beaters 15 is to move the material gradually into the forward end of the body or drum. The cap or head 17 of the body or drum 10 is secured in any suitable way, but preferably by means of studs and pins, as shown in Fig. 2, whereby the head may be readily removable. This head is provided with a large central opening 18, and the cone 19 is made thereon or attached thereto. The beaters or breakers 15

are secured upon the two disks 20, and the outer disk 20 rotates with the small space 21 between it and the inside of the head 17. All of the material that leaves the body of the 5 pulverizer must do so through this annular passage and must pass out through the cone and over the inclined surface thereof. The action of the beaters is to create a strong current of air through the body of the machine, 10 and the finer material arriving at the annular opening 21 is carried by it upon the inclined surface of the cone or deflector 19. The air is in rapid rotation within the cone, and the particles of material as they are rotated 15 rapidly around the axis of the cone are thrown by centrifugal force against the inner surface of the cone and the heavier particles are deflected thereby backward into the discharge-opening of the pulverizer. The finer material is not so much affected by centrifugal force and the current is strong enough to carry the same out of the machine. In order to accelerate the rotation of the air as it is 20 discharged from the annular opening 21, and thereby increase the resistance to the outward flow of the air, and to increase the centrifugal force upon the particles carried by the air, I arrange the wings or blades 24 upon the disk 20 to rotate therewith. These blades 25 interrupt the outward flow of the air to an extent, so that the tendency is to stop the outward progress of material and give it a transverse direction. When the blades are so arranged as to nearly fill the cone, this 30 action and that of centrifugal force becomes so great that only the finest powder will escape from the cone, while when the blades are retracted, leaving a wide space between them and the walls of the cone, the air-current 35 is sufficient to carry out even the heavier particles. For the convenient adjustment of the blades or wings 24 I provide a cross-head 30 upon the forward end of the thrust-rod 7. This cross-head is provided with pins 40 31, which are in inclined slots 32 in the blades 24. Therefore when the rod is thrust forward the blades will be drawn back, while when the rod is drawn back the blades will be forced outwardly. No particular device is provided 45 for drawing the rod back, as the centrifugal force of the blade is sufficient to throw them outward and thrust the rod back with considerable force. This thrust force makes it necessary to employ an antifriction-stop of 50 some kind between the hand-screw 8 and the rear end of the rod 7. In place of this arrangement, however, I may make the blades 24 to lap upon one another, (see Fig. 10,) so that they are practically balanced upon 55 opposite sides of the shaft 5 and the rod upon which they are adjustable. In this way the end thrust upon the rod 7 is minimized. The wings 24 are held in a transverse box 34 on the disk 20, and the sides of this box or guide 60 are removable to permit the removal of the blades or wings. The material discharged from the cone is preferably carried through 65

the large elbow 35 into a capacious dust-collector 36, wherein the material is separated from the air which carries it, the material being discharged through the valve 37 at the lower end of the dust-collector. 70

As the material is advanced toward the outward end of the pulverizer and is rapidly rotated within the same by the beaters the material which is thrown back into the body of the machine by the cone is lifted and thrown upward into the cylinder or chamber or duct 25, leading to the trunk 13, and through the opening 26, arranged above the pulverizer. 80 The pressure of the air would carry the material back; but as this would lessen the pressure I provide in the cylinder a rotating valve or carrier 27, which lifts the material and throws it back into the trunk 13, from which 85 it passes again into contact with the rotating beaters. The valve or elevator 27 rotates very slowly as compared with the beaters or heads 15 upon the disks and allows only a small quantity of air to pass. 90

This particular feed device which I have illustrated in connection with the machine need not be here described. It comprises a vibrating feed-plate and means for regulating the throw of the same. 95

A machine suitable for pulverizing ore and for use with water is shown in Fig. 9, the same comprising the body or drum, the trunk through which the ore and water enter the body, and the centrifugal crushing-rolls 37, 100 which are carried from a yoke 38 on the main shaft. The cone 39 is here arranged at the inner side of the body of the mill and leads into an annular trunk 40, from which the material is discharged through a spout 41. 105 The end of the trunk is closed by a rotating disk, which carries transverse blades or wings 42, that may be adjustable.

It is believed that the operation of the machine will be readily understood from the foregoing.

Having thus described my invention, I claim as new and desire to secure by Letters Patent—

1. The combination, with means for creating a rotating and axially-moving current of air, and for confining said current of air, with an incline or deflector whereon said current impinges, and distinct means for creating a transverse current of air to resist the 115 onward flow of the first-mentioned current, whereby the centrifugal force of the particles carried by the first-mentioned current of air is increased to insure the backward deflection of the heavier particles upon said incline or deflector, substantially as described. 120

2. The combination, with the body or cylinder, of a conical deflector arranged at one end of said body or cylinder, and providing a free outlet therefrom, an inlet-opening in 130 the opposite end of said body or cylinder, means outside of said cone for creating a strong current of air through said body and outward through said cone, means within

said cone to limit and resist the volume and velocity of the air-current passing through said body and cone, and means for regrounding or conveying away the larger particles deflected backward into said body, substantially as described.

3. The combination, with the body or cylinder, of the conical deflector arranged at one end of said body or cylinder, and providing a free outlet therefrom, an inlet-opening in the opposite end of said body or cylinder, means outside of said cone for creating a strong current of air through said body and outward through said cone, adjustable means within said cone to limit and resist the volume and velocity of the air-current passing through said body and cone, and means for conveying away the larger particles deflected backward into said body, substantially as described.

4. The combination, with the cylindrical body, of the rotary beaters arranged therein, the feed-trunk 13, said body provided with an opening 12 to receive material from said trunk, and having a larger opening in its opposite end, the conical deflector arranged about said larger opening, for the purpose described, said body being provided also with an opening 26, a duct leading therefrom to said feed-trunk 13, said opening 26 being at the top of said body to receive the coarse material deflected by said conical deflector, and the conveyer-valve to operate in said duct, substantially as described.

35 5. The combination, of the body or cylinder, having the flaring interior wall or grinding-surface, with the beaters or breakers, and means for rotating the same within said body or cylinder, said body or cylinder having the inlet-opening in one end and the larger outlet-opening in its opposite end, the conical deflector provided about said outlet-opening, means permitting the escape of large particles of material from said cylinder at the circumference of said outlet-opening only, and means adjustable within said conical deflector, adapted to limit and resist the discharge of air or other fluid from said conical deflector, substantially as described.

50 6. The combination, with a conical deflector, of means for creating a current of fluid longitudinally through said conical deflector, to impinge upon the surface thereof, and for rotating the body of fluid within said deflector to limit both the volume and the velocity of said current within said conical deflector, and project the particles carried thereby against said deflector and thence backwardly against the longitudinal current, substantially as described.

7. The combination, with a conical deflector, of the machine-body, the rotary part arranged therein to advance the material, pulverize the same and create a current of fluid through said conical deflector, and distinct adjustable means within said conical deflector for regulating and limiting the onward

and the rotary movement of the said current within the conical deflector, substantially as described.

8. The combination, with the body or casing, having a tapered interior peripheral wall, and having the central or axial inlet and outlet openings and also having a peripheral opening near said outlet-opening, of the cylinder or chamber into which said peripheral opening leads, the rotating valve or elevator arranged in said cylinder or chamber and discharging through the side thereof to return the material to the inlet-opening of said body or casing, and a suitable breaking or crushing mechanism arranged within said body or casing, and adapted to create a forcible fluid current through said body or casing, substantially as described.

9. The combination, with the body or casing having inlet and outlet openings in its ends, of the rotary beaters or breakers arranged within said body or casing to pulverize the material and create an onward current of air or other fluid, the conical deflector arranged about said outlet-opening, and the rotary wings arranged within said conical deflector, as and for the purpose specified.

10. The combination, with the body or casing having inlet and outlet openings in its end, of the rotary beaters or breakers arranged within said body or casing for the purposes described, the conical deflector arranged at said outlet-opening, the rotary wings arranged within said conical deflector to rotate with said beaters or breakers for the purpose specified, and means for adjusting said wings toward and from the interior surface of said conical deflector, substantially as and for the purpose specified.

11. The combination, with the body or casing having the central inlet and outlet openings in its opposite ends, of the conical deflector arranged about said outlet-opening, the central shaft, the thrust-rod within the same, the transversely-movable wings or blades carried by said shaft, to rotate within said conical deflector, and a connection between said thrust-rod and said wings or blades, whereby the latter may be adjusted, substantially as described.

12. The combination, with the body or casing, of the conical deflector, the rotary shaft, the thrust-rod, the transverse wings or blades carried by said shaft and within said conical deflector, said blades being connected with said thrust-rod to be adjusted thereby, and lapping upon one another to equalize the weight upon the opposite sides of the shaft, whereby the centrifugal throw of the blades is minimized, substantially as described.

13. The combination, with a suitable feed device and a trunk or spout, of the body or casing to receive the material therefrom, the rotary beaters or breakers arranged within said body or casing, the conical deflector arranged at the outlet of said body or casing, means within said deflector for increasing the

rotary action of the air-current set up therein by said rotary beaters or breakers, and a collector, for the fine material, connected with the outer end of said conical deflector, substantially as described.

14. The combination, with a suitable feed device and a trunk or spout, of the body or casing to receive the material therefrom, the rotary beaters or breakers arranged within said body or casing, the return-duct between the forward part of the said body and the said inlet thereto, a valve provided in said duct, the conical deflector arranged at the outlet of said body or casing, means for increasing the rotary action of the air-current therein, and a collector, for the fine material, connected with said conical deflector, substantially as described.

15. The combination, with the cylindrical body or casing, having the interior grinding-surface, of the rotary beaters or breakers and means for rotating the same within said body or casing, said casing having an inlet-opening in one end and a larger outlet-opening in the opposite end, the conical deflector provided at said outlet-opening, and the disk 20 rotating with said beaters or breakers, and preventing the escape of material from the body except at the circumference of said outlet-opening, all substantially as and for the purpose specified.

16. The combination, with the cylindrical body or casing, having the interior grinding-surface, of the rotary beaters or breakers and means for rotating the same within said body or casing, said casing having an inlet-opening in one end and a larger outlet-opening in the opposite end, the conical deflector provided at said outlet-opening, the disk 20 rotating with said beaters or breakers and preventing the escape of material from the body or cylinder except at the circumference of said outlet-opening, and transversely-arranged wings also rotating with said beaters and ar-

ranged within said conical deflector to limit 45 and resist the volume and velocity of the currents of air set up by the rotation of said beaters or breakers, substantially as described.

17. In a machine of the class described, the combination, with the cylinder, of the beaters or breakers therein, the feed-trunk opening into said cylinder and through which air is drawn with the material to be ground, a centrifugal separator adjoining said cylinder, permitting the escape of fine material therefrom and returning the coarser particles into the discharge end of said cylinder, a recess in the peripheral wall of said cylinder, into which the material so returned by said separator is thrown by the beaters or breakers 60 in said cylinder, and a duct extending from said recess to said trunk, for the purpose specified.

18. In a machine of the class described, the combination, with the cylinder, of the beaters or breakers therein, the feed-trunk opening into said cylinder and through which air is drawn with the material to be ground, a centrifugal separator adjoining said cylinder, permitting the escape of fine material therefrom and returning the coarser particles into the discharge end of said cylinder, a recess in the peripheral wall of said cylinder, into which the material so returned by said separator is thrown by the beaters or breakers 70 in said cylinder, and a duct extending from said recess to said trunk and containing means permitting the passage of the coarse material but preventing the discharge of air from said cylinder through said recess, substantially as described.

In testimony whereof I have hereunto set my hand this 28th day of April, A. D. 1897.

JOSEPH M. SCHUTZ.

In presence of—

C. G. HAWLEY,
M. E. GOOLEY.
